UNITED STATES PATENT OFFICE

ALBERT I. ELIAS, OF NEW YORK, N. Y.

DESIGN FOR A STORE FRONT

Application filed February 6, 1930. Serial No. 34,438. Term of patent 14 years.

To all whom it may concern:

Be it known that I, ALBERT I. ELIAS, a citizen of the United States, residing in the city, county, and State of New York, have invented a new, original, and ornamental Design for a Store Front, of which the following is a specification, reference being had to the accompanying drawing, forming a part thereof, wherein—

Fig. 1 is a front elevation of the store front;

Fig. 2 is an outline of a section taken in elevation in the plane of the line 2—2, Fig. 1; and

Fig. 3 is an outline of a section taken in the plane of the line 3—3, Fig. 1.

I claim:

The ornamental design for a store front, substantially as shown.

ALBERT I. ELIAS.
